UNITED STATES PATENT OFFICE

144,016

DESIGN FOR A CHILD'S DISH

Edward C. Weideman, Westchester, Ill., assignor, by mesne assignments, to Child Specialties, Inc.,
Chicago, Ill., a corporation of Illinois

Application October 10, 1945, Serial No. 122,709

Term of patent 14 years

(Cl. D44—10)

To all whom it may concern:

Be it known that I, Edward C. Weideman, a citizen of the United States, residing at Westchester, in the county of Cook and State of Illinois, have invented a new, original, and ornamental Design for a Child's Dish, of which the following is a specification, reference being made to the accompanying drawing, forming a part thereof and in which:

Fig. 1 is a perspective view of a child's dish showing my new design;

Fig. 2 is a side elevational view of the dish; and

Fig. 3 is a sectional view taken substantially along the line 3—3 of Fig. 1.

I claim:

The ornamental design for a child's dish, as shown.

EDWARD C. WEIDEMAN.
